UNITED STATES PATENT OFFICE.

FURMAN M. KANDLE, OF ATLANTIC CITY, NEW JERSEY.

DRAFT BLOWER.

Application filed November 2, 1923. Serial No. 672,366.

To all whom it may concern:

Be it known that I, FURMAN M. KANDLE, a citizen of the United States, residing at Atlantic City, in the county of Atlantic and State of New Jersey, have invented new and useful Improvements in Draft Blowers, of which the following is a specification.

This invention relates to a blower or forced draft attachment for furnaces, heating devices, or the like, and an object of the invention is to provide a device which is applicable for attachment to any conventional type of furnace, boiler, heater, or the like, for creating forced draft upwardly therethrough, and also to provide means whereby the direction of passage of the forced draft through the grate may be created to cause the draft to act upon the fuel at any desired place.

Another object of this invention is to provide a draft creating attachment as specified, which includes an adjustable supporting structure by means of which the forced draft creating device may be supported at the principal elevation to fit in the draft door of the heater or the like.

More specifically, the invention comprehends the provision of a body shell having a draft creating fan therein and a hinged closure at the outlet, together with means for supporting said closure in adjusted positions to permit the regulating of the direction of flow of the draft out of the body shell.

Other objects of the invention will appear in the following detail description and in the accompanying drawing wherein:

Figure 1 is a side elevation of the improved draft creating device, showing the same associated with a fragment of a heater.

Figure 2 is a longitudinal section through the improved draft creating device or blower.

Figure 3 is an end elevation of the device.

Figure 4 is a fragmentary top plan of the device.

Referring more particularly to the drawings, the improved draft creating device comprises a substantially frustro-pyramidal body shell 1 which has both of its ends open, and it has a draft creating fan 2 supported therein by a suitable supporting web structure 3. The fan 2 is of any approved type of electric fan and it derives its energizing power from any lamp socket (not shown) through the medium of a suitable connecting cord 4. The fan 2 is positioned adjacent to

the relatively large inlet end of the body shell 1 so that it will draw air inwardly through the open outer or inlet end 5, and force it at an increased rate of speed through the body shell and outwardly through the outlet end 6. In use, the outlet end 6 of the body shell 1 is inserted through the draft opening 7 of a furnace, heater or analogous devices 8 of any approved type, and the air or draft from the body shell is directed upwardly through the grate 9 by means of the hinged door or closure 10. The door or closure 10 is hingedly supported as shown at 11 at the lower side of the body shell 1 and it has side flanges 12 thereon which fit in the body shell. A flexible adjusting strap 13 has one end connected to the upper free end of the closure 10 in any suitable manner, preferably by means of a pin 14 which is inserted in the rolled edge 15 of the closure 10 and forms a pivotal or hinged connection between the closure 10 and the strap 13. The strap 13 is slidably over the upper side of the body shell 1 and is guided by a suitable strap 15. Any suitable type of handle or gripping device 17 may be formed on the free end of the strap 13. An indicating arrow 18 is also carried by the strap 13 and it co-operates with graduations 19 to indicate the effective positions of the closure 10. By regulating the position of the closure 10—that is, by regulating the angle at which it extends relative to the perpendicular—the line of draft issuing from the body shell 1 may be regulated to direct it through any desired portion of the grate 9. This is provided owing to the fact that the fire may be sluggish at the front part of the grate and to make this portion of the fire more active, the closure 10 may be regulated to direct the draft upwardly through the forward portion of the grate only, and by lowering the closure the draft may be directed to pass through any desired portion of the grate or through the entire grate, as necessary.

Owing to the fact that the draft doors of different types of furnaces, heating units, or the like, vary relative to their elevation from the floor, an adjustable supporting structure is provided for the outer end of the body shell 1. The adjustable supporting structure comprises a standard 20 which has diverging legs 21 on its lower end and which passes upwardly through the body shell 1 outwardly of the blower fan 2, as clearly shown

in Figures 2 and 3 of the drawings. The standard 20 is provided with a plurality of vertically spaced transverse openings 22, any one of which is adapted to receive the pin 23 for holding the outer end of the body shell 1 at the desired elevation. The pin 23 is connected to the body shell 1 so as to prevent its loss, by a suitable flexible member 24.

10. It is, of course, to be understood, that the invention may be constructed in various other manners and the parts associated in different relations and, therefore, I do not desire to be limited in any manner except as 15 set forth in the claims hereunto appended.

What I claim is:

1. A draft creating device comprising a body shell, draft creating means therein, the outlet end of said shell adapted to be supported within a furnace door, a standard 20 extending transversely through the inlet end of the body shell, and means co-operating with said standard and body shell for holding the inlet end of the body shell at adjusted elevations.

2. A draft creating device comprising a body shell, draft creating means therein, a closure hinged at its bottom edge to the outer end of said body shell and having angled 30 side edges, and means for adjusting the position of said closure relative to said body shell and for regulating the direction of flow of the draft.

3. A draft creating device comprising a

body shell, draft creating means therein, a closure hingedly connected at the outer end of the body shell, a flexible strap hingedly connected to the upper edge of said closure and slideable along said body shell for moving said closure into adjusted positions to regulate the direction of flow of the draft, and an adjustable support for said body shell.

4. A draft creating device comprising a body shell, draft creating means therein, adjustable means for regulating the direction of the outward flow of the draft from said body shell, a supporting standard extending through said body shell adjacent to its inlet end, and means co-operating with said standard for supporting the body shell at adjusted elevations.

5. A draft creating device comprising a body shell, draft creating means therein, adjustable means for regulating the direction of the outward flow of the draft from said body shell, a supporting standard extending through said body shell adjacent to its inlet end, and means co-operating with said standard for supporting the body shell at adjusted elevations, a closure hingedly connected to the body shell at the lower edge of its outlet end and adapted to be moved for regulating the direction of flow of air out of said body shell.

In testimony whereof I affix my signature.

FURMAN M. KANDLE.
